WEB OR SHEET CUTTING MECHANISM FOR
PRINTING MACHINES

Harry Davis, St. Albans, N. Y., assignor to Irving Trust Company, temporary trustee for R. Hoe & Co., Inc., New York, N. Y., a corporation of New York

Application April 8, 1933, Serial No. 665,096

11 Claims. (Cl. 164—66)

This invention relates in general to web or sheet cutting mechanism for use in connection with cutting and folding cylinders of rotary printing machines, having for its principal object the provision of a knife box assembly with novel spring means for resiliently supporting the cheek blocks.

It is also an object of the invention to provide a knife box assembly of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawings, wherein:

Figure 1 is a diagrammatic view of an embodiment of the invention operatively applied to a cutting cylinder;

Figure 2 is a longitudinal sectional view of one half of the knife box assembly, partly in elevation, with parts broken away;

Figure 3 is an elevational view of the same portion of the assembly as that shown in Figure 2, taken on the line and looking in the direction of the arrow 3 of Figure 6, a portion of the knife blade being broken away to show the manner in which the leaf springs and cheek blocks are mounted;

Figure 4 is a side elevational view of the same half of the assembly disclosed in Figures 2 and 3, as seen in the direction of the arrow 4 of Figure 6, certain parts being broken away to show the relation of other parts;

Figure 5 is a transverse sectional view, taken on the line and as seen in the direction of the arrow 5 of Figure 4;

Figure 6 is a view similar to Figure 5, taken on the line and as seen in the direction of the arrow 6 of Figure 4; and

Figure 7 is a plan view of one of the leaves or flat strips upon pairs of which the cheek blocks are mounted.

With more particular reference to the drawings wherein similar characters of reference indicate corresponding parts in the several views of the preferred form of the invention, A designates a knife box assembly embodying the present invention, the said knife box comprising members or plates 11, 12 which have apertured

extensions as at 13 for securing the said knife box in operative position within the chamber of a cutting cylinder in accordance with conventional practice. Between the said plates, 11—12 which are normally arranged in aligned position and clampingly secured together by screws 14, a cutting blade 15 is arranged, the heads of the screws 14 being countersunk in pockets 16 formed in the member 11 and having stems passing through cut out portions 14' in the blade 15.

The cutting blade 15 is secured between the members 11—12 and extends upwardly between a pair of cheek blocks 17—18 respectively, each cheek block consisting of a plurality of individual blocks or sections arranged longitudinally, end to end, and seated on a plurality of springs, which latter as set forth hereinafter, form an important feature of the present invention. Each pair of springs consist of an upper or outer leaf 19 and a lower or inner leaf 21 which are arranged in opposed relation, each leaf being formed, as best shown in Figure 7, with an ear or projection 22.

The member 11, as best shown in Figures 5—6, is provided with a longitudinally extending shallow recess 23, positioned between an upwardly extending wall 24 and a ridge or lip 25, while the member 12 likewise has a shallow recess 26 between a vertical wall or extension 27 and a ridge or lip 28. The sections of the cheek block 17, also are each formed with a ridge or lip 29, and in corresponding manner the sections of the cheek block 18 have a lip 30. By further inspection of Figures 5—6, it will now be seen that the upper and lower leaves 19, 21 of the above mentioned springs are maintained in position by adjacent portions of the walls 24, 27 and the projecting lips or ridges 25, 28 respectively of the members 11, 12 and the cheek blocks 17, 18, the ears 22 of the said leaves 19, 21 being received in notches 31, 32 provided in the ridges 25, 28, thus preventing displacement or longitudinal movement of the said springs and securing them firmly in operative position for resiliently supporting the cheek blocks.

Slots 33 are provided in each of the cheek blocks, the said slots accommodating pins 34, 35 secured on the vertical extensions 24, 27 of the members 11, 12 thus permitting the said cheek blocks to move in a vertical plane within the limits of the said slots. The pins 34, 35 project through the cheek blocks to a point adjacent either side of the knife 15.

Means are provided for adjusting the knife blade 15 in a vertical plane. The said means consisting of screws 36, located at either end of the member 12, and threadedly engaged in a

shelf 37 formed as a portion of the member 12, the said screws 36 having enlarged heads 38 which are received in slots or cut portions 39 formed in the lower portion of the cutting blade 15. The 5 bottom edge of the blade 15 is also engaged by an adjacent inner portion of the heads of a series of other screws 41 which are also threadedly engaged in the shelf 37 and which serve to brace the blade 15 in the adjusted position selected, as 10 best shown in Figure 5.

The knife box assembly A is adapted for insertion into any conventional type of cutting cylinder such as that illustrated in Figure 1, and is secured thereto by screws (not shown) passed 15 through the apertured extensions 13 into the body of the cutting cylinder. A cutting abutment 43 arranged on a folding cylinder 44 coacts with the knife blade 15 in severing the web 45 engaged between the nip of the folding and cutting cylinders, as the said cylinders rotate. 20

When desired or necessary, the above-described knife box assembly may be quickly taken apart for inspection of the various elements thereof by merely unthreading the screws 14.

25 Heretofore, considerable difficulty has been experienced in helical type springs used to support the cheek blocks by reason of the limited space available in the interior of the knife box, necessitating the use of comparatively short springs 30 which did not provide sufficient resiliency to properly maintain the cheek blocks in operative position. In addition the said helical springs are quite prone to break in use. These operating disadvantages have been in large measure overcome by the leaf type springs hereinbefore described which are particularly adapted not only to be received into a comparatively restricted passageway, but also, by reason of their design and construction and their engagement with the co- 35 acting adjacent parts of the knife box, to be held securely against displacement while maintaining the cheek blocks in operative position with a uniform pressure. 40

It will be understood that the invention may be 45 embodied in other specific forms without departing from the spirit or essential attributes thereof, and it is therefore desired that the present embodiment be considered in all respects as illustrative and not restrictive, reference being had to the appended claims rather than to the foregoing 50 description to indicate the scope of the invention.

What I claim is:

1. A knife box of the character described comprising a plurality of cheek blocks, means for securing said cheek blocks in operative relation, a knife arranged between the cheek blocks, and leaf springs for resiliently maintaining the said cheek blocks in operative position, said leaf springs being adapted to elongate in a plane normal to the plane of movement of the said cheek blocks. 55

2. A knife box assembly of the character described comprising cheek blocks, means for securing the cheek blocks in operative position, a knife arranged between the cheek blocks, and non-helical means for resiliently supporting the said cheek blocks, said non-helical means comprising outer and inner sections arranged in opposed relation. 60

3. A knife box assembly of the character described comprising cheek blocks, means for securing the cheek blocks in aligned relation, a knife blade secured in said means and extended upwardly between the cheek blocks, a plurality of threaded means for adjusting the knife blade, and a plurality of pairs of leaf springs arranged 65

on either side of said knife and positioned between the cheek blocks and the means, each of said pairs of leaf springs comprising an outer section and an inner section, said sections being arranged in opposed relation. 80

4. A knife box assembly of the character described comprising a pair of members arranged side by side, a pair of cheek blocks secured between said members, a knife blade adjustably secured between the members and extending upwardly between the cheek blocks, means formed in said cheek block and said means for firmly securing a plurality of pairs of leaf springs therebetween, and other means for preventing longitudinal movement of the leaf springs relatively to the said members and cheek blocks. 85

5. In a device of the character described, a pair of members arranged side by side, a pair of cheek blocks secured to said members, a knife blade adjustably mounted between members and extended upwardly between the cheek blocks, a pair of threaded members for raising and lowering the knife blade, a plurality of other threaded members for bracing the knife blade, leaf springs arranged between the cheek blocks and the members, and means formed in the said leaf springs for restraining same from longitudinal movement relatively to the cheek blocks and the first mentioned pair of members. 90

6. A knife box of the kind described comprising a pair of members arranged in juxtaposed relation, a recess provided between said members, flat springs secured in the recess and seated on said members, a cutting blade positioned between the cheek blocks and the members and slideable relatively thereto, a plurality of threaded means for moving said cutting blade relatively to said member and cheek blocks, and other means integral with said springs for anchoring same in operative position. 100

7. A device of the kind described comprising a pair of members arranged in aligned relation, recesses formed in said members, a plurality of non-helical springs arranged in said recesses in pairs, each pair having an outer section and an inner section, a pair of cheek blocks arranged in the recesses and seated on said springs, guide means arranged on said cheek blocks and said members for maintaining said springs in operative aligned relation, a cutting blade secured between said cheek blocks and members, a plurality of screws adapted to engage a lower edge of said cutting blade for adjusting same relatively to said members, and instrumentalities for anchoring said springs against translational movement within said device. 110

8. A device of the kind described comprising a pair of members arranged in aligned relation, a plurality of means for securing the members in said aligned relation, a cutting blade positioned between said members, a cheek block arranged on either side of the blade, a plurality of non-helical resilient means engaging opposed surfaces of the cheek blocks and members, and means threadedly engaged in one of the plates for raising and lowering the cutting blade relatively to the cheek blocks and the said members, said resilient means including springs arranged in pairs, each pair comprising an outer leaf and an inner leaf. 120

9. In a cutting mechanism for a printing machine folder, a rotary carrier having a recess, a knife secured in the recess, cheek blocks on either side of the knife, and flat springs between the cheek blocks and the bottom of the recess, where- 125

by the cheek blocks are yieldingly supported; said springs having members to engage coating members of said recess and of said cheek blocks to secure the springs in operative alignment.

5 10. In a cutting mechanism for a printing machine folder, a rotary carrier having a recess, a knife secured in the recess, cheek blocks on either side of the knife supported to move only in a plane substantially radial to the axis of the carrier, flat springs in the bottom of the recess, and other flat springs in the recess engaging the first springs.

11. In a cutting mechanism for a printing machine folder, a rotary carrier having a recess, a knife secured in the recess, cheek blocks on either side of the knife supported to move only in a plane substantially radial to the axis of the carrier, flat springs in the bottom of the recess, means for securing them to resist longitudinal motion, other flat springs in the recess engaging the first springs, and means to secure said last mentioned springs to the cheek blocks to resist longitudinal motion.
